(57) **CLAIM**

The ornamental design for a cutting tool and handle, as shown and described.

DESCRIPTION

FIG. 1 is a perspective view of a first embodiment of a cutting tool and handle showing my new design;

FIG. 2 is a front view of the cutting tool of FIG. 1;

FIG. 3 is a back view of the cutting tool of FIG. 1;

FIG. 4 is a right side elevational view of the cutting tool of FIG. 1;

FIG. 5 is a left side elevational view of the cutting tool of FIG. 1;

FIG. 6 is a top view of the cutting tool of FIG. 1;

FIG. 7 is a bottom view of the cutting tool of FIG. 1;

FIG. 8 is a perspective view of the second embodiment of a cutting tool and handle showing my new design;

FIG. 9 is a front view of the handle of FIG. 8;

FIG. 10 is a back view of the handle of FIG. 8;

FIG. 11 is a right side elevational view of the handle of FIG. 8;

FIG. 12 is a left side elevational view of the handle of FIG. 8;

FIG. 13 is a top view of the handle of FIG. 8; and,

FIG. 14 is a bottom view of the handle of FIG. 8.

The broken line showing in the drawings are included for the purpose of illustrating unclaimed portions of the cutting tool and handle and forms no part of the claimed design.

1 Claim, 8 Drawing Sheets
